UNITED STATES PATENT OFFICE.

GEORGE W. BROWN, OF BOSTON, MASSACHUSETTS, ASSIGNOR TO TUBULAR RIVET & STUD COMPANY, OF BOSTON, MASSACHUSETTS, A CORPORATION OF MASSACHUSETTS.

HOOK-SETTING MACHINE.

1,080,194.

Specification of Letters Patent. Patented Dec. 2, 1913.

Application filed March 10, 1913. Serial No. 753,280.

To all whom it may concern:

Be it known that I, GEORGE W. BROWN, a citizen of the United States, residing at Boston, in the county of Suffolk and State of Massachusetts, have invented certain new and useful Improvements in Hook-Setting Machines; and I do hereby declare the following to be a full, clear, and exact description of the invention, such as will enable others skilled in the art to which it appertains to make and use the same.

The invention relates to machines for setting lacing hooks or studs, and more especially to the devices for positioning the quarters of the upper preparatory to setting the first hook or stud therein.

The invention is intended primarily as an improvement in the hook setting machine shown and described in the patent to Glass, No. 811,841, dated February 6, 1906, although it is not confined in its application to this machine, but may be embodied with advantage in other forms of hook setting machines.

In the machine of the above patent the quarters of the upper are positioned preparatory to setting the first of a series of hooks therein by end gages, one of which is secured to the head carrying the combined anvil and punch, and the other of which is mounted upon the frame of the machine, the former gage being used to position the left quarter, *i. e.*, the quarter in which the upper hook is the first hook set, and the latter gage being used to position the right quarter, *i. e.*, the quarter in which the lower hook is the first hook set. In adjusting this machine for different sizes or classes of shoes it is necessary to adjust the combined anvil and punch to vary the spacing of the hooks, and to independently adjust the gage which determines the position of the right quarter. This double adjustment requires time and care on the part of the operator, in order that the gage may be accurately positioned to secure the proper positioning of the hooks.

It is the primary object of the present invention to provide novel and improved means for adjusting the work feeding and positioning devices which will enable the proper adjustments to be more readily and quickly made, without special care on the part of the operator.

To this end the invention contemplates the provision in a hook setting machine pro-

vided with stock feeding means for spacing the hooks of means for determining the position of that gage for the quarter of the upper in which the lower hook is the hook first set in adjusting the stock feeding means to vary the spacing of the hooks for different sizes or classes of shoes. This means preferably comprises connections through which the stock feeding means and gage are simultaneously set or adjusted for properly positioning and spacing the hooks in quarters of different sizes or classes.

The various features of the invention will be readily understood from an inspection of the accompanying drawings and the following detailed description of the mechanism illustrated therein.

In the drawings, Figure 1 is a front elevation of a hook setting machine embodying the invention in its preferred form; Fig. 2 is a vertical sectional view showing a part of the mechanism for varying the spacing of the hooks; Fig. 3 is a detail sectional plan view showing the devices for simultaneously adjusting the feeding means and the upper positioning gages; and Fig. 4 is a detail elevation showing the cam through which one of the gages is adjusted.

In the drawings the invention is shown in the hook setting machine fully shown and described in the patent to Glass above referred to. This machine is provided with hook setting devices including the combined anvil and punch 1, which is mounted to reciprocate vertically in a horizontally reciprocating head 2, and acts to feed the stock to properly space the hooks. The punch carrying head 2 is reciprocated to automatically space the hooks by the cam 8 and connections comprising the yoke 4, the adjustable rod 5, and the block 6 carrying the stud 7 engaging the slotted arm 8 carried by the sleeve 9 which is connected with the head.

The length of the feeding stroke of the head and punch carried thereby is varied in accordance with the size of the shoe upper in which the hooks are to be set by adjusting devices which shift the stud 7 in the slotted arm 8, the slot being so arranged that the punch is advanced to the setting point, whatever the adjustment of the stud. These devices comprise a bell crank lever 10 one arm of which is connected by a link 11 with the block 6, and the other arm of which is provided with a gear segment 12

engaged by a gear segment 13 formed on a spacing lever 14. The spacing lever carries a pointer 15 arranged to indicate the adjustment of the stock feeding mechanism upon a graduated dial 16. The construction and mode of operation of these parts is the same as the construction and mode of operation of the corresponding parts in the patent above referred to.

10 The left quarter of the shoe is properly positioned for the setting of the upper hook by an end gage 17 which is secured to the head 2 in fixed position with relation to the feeding and setting punch 1, so that it is adjusted with the punch when the feeding mechanism is adjusted for different spacings of hooks, and insures the setting of the upper hook at a definite distance from the upper edge of the quarter, whatever the 15 spacing of the hooks may be. The right quarter of the shoe is properly positioned for setting the lower hook by an end gage 18 arranged to engage the upper corner of the quarter, and carried by a slide rod 19. The gage supporting rod 19 is mounted to slide in a bearing formed in a bracket 20 adjustably secured to an arm 21 which is in turn secured to the frame of the machine. An edge gage 22 is arranged between the gages 17 and 18, and cooperates with these gages in properly positioning the right and left quarters of the upper, as indicated in Fig. 3.

In order that the gage 18 may properly 35 position quarters of different sizes, the position of the gage with reference to the feeding and setting punch, and with reference to the setting point, must be varied in accordance with the size of the upper to be 40 operated upon. In accordance with the present invention the proper position of this gage for any given size or class of upper is determined in adjusting the feeding mechanism to properly space the hooks in such 45 upper. In the preferred form of the invention shown, the means which determines the position of the gage also moves the gage into proper position. As shown, this means comprises a lever 23, one end of which is 50 connected by a link 24 with the gage carrying rod 19, and the other end of which is provided with a cam plate 25 engaged by a pin 26 projecting from the bell crank lever 10. A spring 27 acts to hold the cam 25 55 constantly in engagement with the pin 26. The pin 26 is secured to the lever 10 by a clamping screw 28. The hole through the pin 26 is eccentric, so that the pin may be adjusted to bring it into proper relation to 60 the cam surface in applying the invention to existing machines. The surface of the cam 25 is so shaped, and the parts are so proportioned that an adjustment of the spacing lever 14 to properly space the hooks 65 in any given size or class of upper will also

adjust the gage 18 to properly position the right quarter so that the lower hook will be set at the proper distance from the upper eyelet and from the upper edge of the quarter.

70 While it is preferred to employ the specific construction and arrangement of parts shown and described in embodying the invention in the machine of the patent above referred to, it will be understood that this construction and arrangement is not essential to the broader features of the invention, and may be varied and modified as found desirable or best suited to the construction of the machine in which the invention is to 75 be embodied.

80 Having explained the nature and object of the invention, and specifically described one form of machine in which it may be embodied, what is claimed is:—

85 1. A hook setting machine, having, in combination, stock feeding means, a gage for positioning an upper to set the lower hook first, and common means for simultaneously adjusting the stock feeding means 90 and gage for different sizes.

95 2. A hook setting machine, having, in combination, setting devices, two end gages for the upper ends of right and left quarters respectively, and common means for 100 simultaneously adjusting the gages for different sizes.

105 3. A hook setting machine, having, in combination, stock feeding means adjustable for different sizes, an end gage for positioning an upper to set the lower hook first, and means for determining the position of the end gage in adjusting the stock feeding means.

110 4. A hook setting machine, having, in combination, a punch and set, means to move the same laterally to feed the stock, an end gage movable therewith, an independently mounted end gage, and common means for varying the feeding movement of the punch and set and the position of the latter gage.

115 5. A hook setting machine, having, in combination, a punch and set, means to move the same laterally to feed the stock, an end gage movable therewith, an independently mounted end gage, and common means for simultaneously varying the feeding movement of the punch and set and the position of the latter gage.

120 6. A hook setting machine, having, in combination, a punch and set, means to move the same laterally to feed the stock, an end gage movable therewith, an independently mounted end gage, means for varying the feeding movement of the punch and set, and connections between said means and the latter gage for varying the position of the gage in accordance with the feeding movement of the punch and set.

7. A hook setting machine, having, in combination, a punch and set, means for moving the same laterally to feed the stock, an independently mounted gage, a spacing lever and connections for varying the feeding movement of the punch, and connections between the lever and the gage comprising a gage positioning cam.
8. A hook setting machine, having, in combination, stock feeding means, a gage 18
- for positioning an upper to set the lower hook first, a slide 19 carrying the gage, a cam lever 23 connected to the slide, means for adjusting the stock feeding means for different sizes including a lever 10, and a 15 pin on the lever engaging the cam lever 23.
